UNITED STATES PATENT OFFICE.

JOSEPH CALLAWAY, OF BILOXI, MISSISSIPPI.

COTTON CHOPPER.

Application filed March 16, 1926. Serial No. 95,101.

This invention relates to certain improvements in cotton choppers and it is an object of the invention to provide a device of this kind comprising a scraping blade supported for swinging movement in a direction transverse to the direction of travel of the machine, together with means for normally imparting such transverse movement to the blade at intervals during the travel of the machine.

It is also an object of the invention to provide a machine of this kind of a walking type and wherein means is provided to assure effective coaction with the operator.

The invention consists in the details of construction and in the combination and arrangement of the several parts of my improved cotton chopper whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in top plan illustrating a machine constructed in accordance with an embodiment of my invention;

Figure 2 is a vertical sectional view taken longitudinally through the device as herein disclosed with certain of the parts in elevation;

Figure 3 is a view in side elevation of the device as herein set forth;

Figure 4 is an enlarged fragmentary view in vertical section illustrating a means for imparting transverse swinging movement to a scraping blade;

Figure 5 is a detailed sectional view taken substantially on the line 5—5 of Figure 4;

Figure 6 is a view partly in section and partly in top plan of one of the operating members herein disclosed for a scraping blade;

Figure 7 is a view similar to Figure 6 but illustrating said operating member in a second position.

As disclosed in the accompanying drawings, F denotes an elongated frame of requisite dimensions and which is provided rearwardly of its longitudinal center with a transversely disposed axle or shaft 1 ro-

tatably supported by the side members 2 of the frame F. Fixed to the extremities of the shaft or axle 1 are the ground engaging wheels 3 of desired diameter.

The shaft 1 at a point between the side members 2 of the frame F has fixed thereto a gear 4 meshing with a smaller gear 5 fixed to the transversely disposed shaft 6 positioned in advance of the axle or shaft 1 and 60 rotatably supported by the side members 2 of the frame. Also fixed to this shaft 6 is a larger gear 7 meshing with a smaller gear 8 fixed to the shaft 9 extending transversely of the frame F at a desired point in advance 65 of the shaft 6 and rotatably supported by the side members 2 of the frame. The gears 4, 5, 7 and 8 are of such ratio as the requirements of practice may prefer.

The shaft 9 extends beyond each side of 75 the frame F and fixed to each of said extended portions is a drum 10 provided in its periphery with a circumferentially disposed groove 11 having a portion 12 laterally offset to provide the spaced cam groove portions 14.

Extending outwardly from each of the side members 2 of the frame F is a loop bracket 15. This bracket 15 is substantially radial to the adjacent drum 10 and pivotally 85 connected, as at 16, to the end members 15' of the bracket 15 are the vertically disposed side members 17 of a substantially square frame 18. The top member 18' of the frame 18 at substantially its axial center is provided with an inwardly disposed pin or finger 19 which extends within a groove 11 in the adjacent drum 10 so that as the drum 10 is rotated, the cam portions 14 of said groove will cause the frame 18 at predetermined intervals during the travel of the machine to have swinging movement in a direction transverse to the direction of travel of the machine.

Depending from and extending inwardly 100 from each of the frames 18 are the downwardly converging arms 20, the free end portions of said arms being provided with a depending shank 21 to the lower or free end portion of which is secured a scraping 105 blade B. This blade B is preferably disposed at an angle of about fifteen degrees with respect to the longitudinal axis of the frame F or to the path of travel of the machine. As is particularly illustrated in 110 Figure 5, it is to be noted that the two blades are oppositely disposed and converg-

ing inwardly and forwardly with the inner end portion of one of the blades B extending slightly behind the second blade B.

In practice, the machine travels along a row of young cotton plants and normally the blades B are at their innermost positions, as illustrated in Figure 5. When so arranged, the blades B operate to cut out cotton plants and also grass, weeds and the like, the angular relation of the blades causing such plants and the like to slide to the sides of the row. At predetermined intervals, however, the cam portions 14 of the grooves 11 in the drums 10 will impart lateral swinging movement to the blades B in a direction transversely of the row and to an extent outwardly to cause the blades B to separate a distance sufficient to avoid certain of the cotton plants before said blades return to their innermost or normal positions. By this means, stands of cotton plants are provided at requisite intervals along the row and thus effecting a desired cutting out or chopping with convenience and facility.

Pivotaly connected, as at 22, with the side members 2 at the forward portions thereof are the side members 23 of a gauge member G, said member being herein disclosed as substantially in the form of an inverted U. These side members 23 extend above and below the frame F and rotatably supported by the lower end portion of each of the side members 23 of the member G is a ground engaging wheel 24. The intermediate member 25 of the gauge member G has pivotally connected, as at 26, with the central portion thereof an extremity of a link 27. This link 27 extends forwardly of the frame F and its outer end portion is provided along its lower margin with a toothed rack 28 adapted to be adjustably engaged with the marginal portion of a plate 29 defining an opening 30 therein through which the link 27 is extended. The plate 29 extends upwardly from the forward end member 31 of the frame F and the link 27 is constantly urged downward to maintain requisite locking engagement with the plate by a spring 32 carried by the upper portion of the plate 29 and pressing down on the link 27 from above.

The rear end member 33 of the frame F closely adjacent to the ends thereof is provided with the upstanding posts 34 the upper extremities of which being connected by a rod 35 providing a hand grasp or handle adapted to be engaged by the operator to facilitate the requisite travel of the machine as the operator walks therebehind.

To further facilitate the travel of the machine, the shaft or axle 1 has freely engaged with the extremities thereof and inwardly of the wheels 3 the rearwardly di-

rected and vertically swinging bars 36 the outer end portions of which being connected by the transversely disposed bar 37. Extending upwardly from the bar 37 are the elongated arms 38 terminating in the forwardly directed and downwardly facing hook members 39 which are adapted to engage over the shoulders of the operator with the arms 38 rearwardly arranged. By this means, further pushing action may be imposed upon the machine by the operator and thereby materially facilitating its travel.

It will also be understood that by a swinging adjustment of the gauge member G, the extent of penetration of the blades B may be regulated or controlled as desired, or said blades may be maintained at a sufficient distance above the ground surface when it is desired to render the blades inoperative, such as when transporting the device from one locality to another.

From the foregoing description it is thought to be obvious that a cotton chopper constructed in accordance with my invention is particularly well adapted for use by reason of the convenience and facility with which it may be assembled and operated, and it will also be abvoius that my invention is susceptible of some change and modification without materially departing from the principles and spirit thereof and for this reason I do not wish to be understood as limiting myself to the precise arrangement and formation of the several parts herein shown in carrying out my invention in practice except as hereinafter claimed.

I claim:—

1. A cotton chopper comprising, in combination, a portable frame, scraper blades supported by the frame for swinging movement in a direction transverse to the direction of travel of the frame, and means operating to intermittently impart swinging movement to the blades, said means, when the frame is in transit maintaining the blades in working position with one of the blades partially extending behind the other for a longer period of time than when the blades are in separated relation.

2. A cotton chopper comprising, in combination, a portable frame, scraper blades supported by the frame for swinging movement in a direction transverse to the direction of travel of the frame, and means operating to intermittently impart swinging movement to the blades, said means normally maintaining the blades in working position with one of the blades partially extending behind the other, said blades being disposed on converging inclines.

In testimony whereof I hereunto affix my signature.

JOSEPH CALLAWAY.
